UNITED STATES PATENT OFFICE.

JAMES S. HEATH, OF BRANTFORD, ONTARIO, CANADA, ASSIGNOR TO J. O. WISNER, SON & CO., OF SAME PLACE.

SPRING-HOE.

SPECIFICATION forming part of Letters Patent No. 281,874, dated July 24, 1883.

Application filed February 15, 1883. (No model.)

To all whom it may concern:

Be it known that I, JAMES SAMUEL HEATH, a subject of the Queen of Great Britain, residing at the city of Brantford, in the county of 5 Brant, in the Province of Ontario, Dominion of Canada, have invented certain new and useful Improvements in Spring-Hoes, of which the following is a specification.

The object of the invention is to simplify the 10 construction of the spring-hoe, and to arrange it so that the drill-hoe can be taken off and the cultivator-tooth put in its place without removing a single bolt or disconnecting the lifting-chain; and it consists in the formation and 15 arrangement of parts, as hereinafter specified.

Figure 1 is a perspective view of the spring-hoe complete. Fig. 1^a is an enlarged view of the projection *d*, showing the form of the notches. Fig. 2 is a detail of a drill-hoe. Fig. 20 3 is a detail of a cultivator-tooth. Fig. 4 is an enlarged perspective detail of the lever *C*. Fig. 5 is an enlarged perspective detail of the lever *C*, having a hooked end instead of the projection *c'*. Fig. 6 is a longitudinal section of Fig. 4. Fig. 7 is a longitudinal section of Fig. 5. Figs. 8 and 9 are details of the brace *B* when provided with a hole to fit over the projection *c'*, and a stud, *b*, to fit into the 25 notch formed in the projection *d*. Fig. 10 is 30 a detail of the brace *B* when notched to fit over a fixed stud in the projection *d*, and provided with a pin to fit into the hooked end of the lever *C* when formed as shown in Figs. 5 and 7. Fig. 11 is an enlarged detail of the cap 35 *I* and link *J*.

D is a drill-hoe having on its upper and forward face a projection or lug, *h*, intended to fit within the drag-bar *A*. The outer or bottom edge of the lug and the bottom of the notch 40 or gap *h''* should be struck from a common center. *d* is a projection situated beneath the lug *h*, and having notches cut upwardly in its lower edge, to receive the pin or stud *b* on the end of the brace *B*. The upper part of these 45 notches is cut at such an angle that the particular notch into which the stud *b* may at the time be fitting shall be at about right angles to the brace, while the lower part of each notch is cut at an angle of about forty-five degrees 50 to its upper part.

A is the drag-bar, made in the usual form, except that one-half of it is continued beyond the point where the hoe is pivoted, and has on its end a cap, *I*. This cap is a hollow saucer-like casting shouldered to pass underneath the 55 drag-bar, and slotted on its upper side, so as to allow a limited motion to the link *J*, which is held by and pivoted on a bolt, *K*, passing through the drag-bar, cap, and link. To this link is connected the chain for attaching the 60 hoe to the lifting-roller, thereby enabling the hoe to be removed without disconnecting the lifting-chain, which in other machines is connected to the hoe.

K' is a strap passing underneath the lug *h*, 65 up each side of the drag-bar, and is provided with shoulders which project inwardly, so as to fit over the top edge of the drag-bar.

The locking-lever *C*, as shown in detail, is a short casting having a stud or pivot-pin, *e*, 70 cast on each side, upon which it is pivoted to the drag-bar. The lever *C* is also grooved throughout its length to receive the lower edge of the brace *B*. One of the sides of the locking-lever is carried upwardly beyond the 75 main body, where it terminates in a hook-formed projection, *c'*, having an oval-shaped head on its upper end. This head is of such a size and shape that the hole in the end of the brace *B* may fit over it, and by a twisting motion be made to embrace the projection *c'*. It will be seen by this peculiar construction that it is impossible to disconnect the brace from the locking-lever when in working position. At the lower end of the locking-lever are cast 85 two cheeks, *c''*, which are fitted with a small bolt or rivet passing through and made fast to the same.

H is a casting bolted firmly between the plates forming the drag-bar, and extending below it to form a support for the end of the plunger *G*.

S is a spiral spring supported by the rod or plunger *G*, which plunger is provided with a collar and a tenon having a notch in the end. 95 The tenon fits between the cheeks *c''* of the locking-lever *C*, and the notch fits over the small bolt or rivet, and is firmly retained in contact by the pressure caused by the expansion of the spring *S*. 100

Fig. 3 represents a cultivator-tooth provided with notched lugs *d*, similar to those on the drilling-hoe, with which it is interchangeable.

It will be seen from the foregoing description that by the construction and arrangement of parts herein described certain new and important features are introduced—for instance, the rapidity and ease with which the drilling-hoe may be replaced by the cultivator-tooth, or vice versa, which change may be effected without loosening a nut or removing a single bolt, by simply depressing the lower end of the brace *B* until its pin *b* is clear of the notch into which it may at the time be fitting. The bottom part of the hoe or cultivator-tooth is then pulled backwardly and upwardly till the gap $1\frac{1}{2}$ " in the lug *h* is in line with the drag-bar *A*, when the hoe or tooth may be withdrawn without any further displacement of the parts.

In order to change the angle of the hoe or tooth, it is merely necessary, after liberating the pin *b* by depressing the brace *B*, as before mentioned, to swing the hoe or tooth till the notch corresponding with the desired angle is opposite to the said pin *b*, when it will be carried upward, and there firmly retained by the pressure of the spring *S*, acting against the locking-lever *C*, which supports the brace *B*.

It will be noticed that in the construction of my locking device the relative position of the three centers of motion—viz., pin *b* at the lower end of the brace, projection *c* at upper end of locking-lever, and the pivot of the latter—is maintained by the contact of the said brace with the step *f* in the groove of the locking-lever, and not, as usual, by the latter resting upon the top edge of the drag-bars. This allows the spring to exert pressure on the lower part of the brace *B*, to keep the brace in proper connection with the hoe or tooth. By having the hole in the upper end of the braces made on one side of the longitudinal center line, the tension of the locking device may be altered by turning the brace upside down. The position of this hole *i* will be understood on reference to Figs. 8 and 9. In these figures the location of the stud *b* is also shown. So far in the specification I have described the lever *C* as having a projection, *c'*, to connect with the brace *B*, and the brace as having a stud, *b*, to connect with the projection *d*, formed on the hoe *D* or cultivator-tooth. Of course the same result will be attained by forming the lever *C* as shown in Figs. 5 and 7, in which a hooked end, *g*, is shown as an equivalent for the projection *c'*. When the lever is made in this way, it is of course necessary to provide a stud, *j*, (see Fig. 10,) which stud is designed to fit into the hooked end *g* when the edge of the brace rests on the step *f*.

While I think the notches shown in the projection *d* will be found preferable, the same end might be accomplished by putting a fixed stud in the projection *d* and forming notches in the end of the brace *B*, as shown in Fig. 10.

What I claim as my invention is—

1. In a drill-hoe or cultivator-tooth pivoted

to the drag-bar, the combination of a projection formed on the hoe or tooth below the pivot, and having notches formed in it to receive the pin connecting it to the brace, each of said notches being constructed with different inclines, substantially as and for the purpose specified.

2. In a drill-hoe or cultivator-tooth having a projection to fit within the drag-bar, and a notch formed on the top side of the said projection to fit onto the bottom side of the pivot-pin, the combination of a strap bolted or otherwise fastened to the drag-bar, and extending below the notched projection for the purpose of holding it against the pivot-pin, as specified.

3. In a spring-hoe, a locking-lever pivoted to the drag-bar, in combination with a brace the upper end of which is connected to the locking-lever above its pivot, while the portion of the locking-lever extending below its pivot forms a support for the brace, substantially as and for the purpose specified.

4. In a spring-hoe, substantially as described, and in combination with the brace and plunger thereof, the lever *C*, having means for connection with said plunger, and a hook for removably securing it to the brace, as shown.

5. In a spring-hoe, a locking-lever provided with pivot-pins to connect it to the drag-bar, and a hooked end to connect it to the brace, in combination with a step formed on or by the top edge of the locking-lever, for the purpose of supporting the brace between the point where it connects with the lever and the point where it is attached to the hoe.

6. In a spring-hoe, a locking-lever pivoted to the drag-bar, and removably connected at its upper end to the hoe-brace by the hook *g*, in combination with a spring arranged to exert an upward pressure on the lower end of the locking-lever, substantially as and for the purpose specified.

7. In a spring-hoe in which the upper end of the hoe-brace is connected to the locking-lever above its pivot, while the portion of the locking-lever extending below its pivot forms a support for the brace, the combination of a hole or pin made in or formed upon the upper end of the brace at a point on one side of the longitudinal center line of the said brace, substantially as and for the purpose specified.

8. In combination with the drag-bar and a recessed cap supporting the same, the links *J*, working loosely in said cap, and the lifting-chain, as set forth.

9. The cap *I*, recessed as shown, and having lugs to engage the under side of the drag-bar, combined with the links *J*, the drag-bar, the lifting-chain, and the hoe, as set forth.

Toronto, January 24, 1883.

JAMES S. HEATH.
